N. H. COLEMAN.
WHIP HOLDER.
APPLICATION FILED APR. 22, 1913.

1,100,122.

Patented June 16, 1914.

UNITED STATES PATENT OFFICE.

NORMAN H. COLEMAN, OF FIBRE, MICHIGAN.

WHIP-HOLDER.

1,100,122.

Specification of Letters Patent. Patented June 16, 1914.

Application filed April 22, 1913. Serial No. 762,924.

To all whom it may concern:

Be it known that I, NORMAN H. COLEMAN, a citizen of the United States, residing at Fibre, in the county of Chippewa, State of Michigan, have invented certain new and useful Improvements in Whip-Holders; and I do hereby declare the following to be a full, clear, and exact description of the invention, such as will enable others skilled in the art to which it appertains to make and use the same.

This invention relates to whip holders.

An object of the invention is to provide an improved whip-holder which may be secured to the dash-board of a buggy or other vehicle, and which will securely hold the whip and effectually prevent it from jostling and rattling, so as to eliminate the usual annoyance and to prevent wearing of the whip handle.

Another object is to provide a whip holder of this character which lies substantially flat against the dash-board, and therefore occupies but little of the useful space within the vehicle, and is not easily disarranged or broken by contact of boxes, baggage, etc., being carried in the front of the vehicle.

Another object is to provide a whip holder of this character in which the weight of the whip assists the springs in securely holding the whip.

Another object is to provide a whip holder of this character, which is strong, durable, comparatively inexpensive, and thoroughly efficient.

Other objects and advantages may be recited hereinafter and in the claims.

In the accompanying drawings, which supplement this specification: Figure 1 is a side elevation view of my improved whip holder with one side of the casing eliminated. Fig. 2 is a similar view showing the whip holder in open position. Fig. 3 is a top plan view of the complete whip holder, and Fig. 4 is an enlarged sectional detail view of one of the lower clamping blocks or jaws.

Referring to these drawings, in which similar reference characters correspond with similar parts, throughout the several views: The casing 5 is formed from two similar sheet metal blanks, each being provided with a horizontal bottom flange 6, end flanges 7 and top flanges 8, all of these flanges terminating in a plane at right angles to the vertical side walls or plates 9. These side

walls are slotted or recessed at 10, for the reception of pivots 11 and have their ends slidably seated therein and have their respective middle portions secured to the bell cranks 12. Each of these bell cranks carries an upper clamping jaw 13 and a lower clamping jaw 14, pivotally mounted on pins 15 and 16 respectively. Flat springs 17 are carried by the upper ends of the long arms 18 of the bell cranks, and these springs contact with the respective upper clamping jaws for pressing their upper ends firmly against the whip. The lower clamping jaws are provided with rubber cushions or clamping elements 19, each being formed with a flange 20 at its upper end. These flanges are inwardly directed toward each other and are concaved, so as to fit snugly around the whip handle above the usual knob or enlargement 75 adjacent to the end of the whip handle. The medial and lower portions of the elements 19 are also concaved so as to fit snugly around a whip handle. The clamping jaws or blocks 13 need not essentially be cushioned, but may be provided with cushions of rubber or felt when desirable; the inner or gripping surfaces of these blocks 13 being concaved and adapted to fit snugly against the sides of the whip handle.

A link 21 is pivoted to one of the blocks or jaw members 14 by means of a pin 22, while a similar pin extends through the other block 14 and through a slot 23 of said link, said pin being slidable through 90 said slot. The normally lower end of the lower arm 24 of the bell crank is substantially at right angles to the lower edge of said arm, while the upper edge thereof is formed with an obtuse angle or an abutment 25 which stands also at an obtuse angle to the end 26 of said arm, while the pivot 16 is slightly below the middle of the block, so that when the arms 24 are raised into their upper positions respectively, the force of gravity causes the blocks 14 to fall back and rest on said abutments. Therefore, it will be seen that the tops of the blocks are separated sufficiently for receiving the whip handle therebetween, and that when the whip handle is inserted in the casing it passes between the clamping blocks 13 and is guided centrally by the guide lugs 27, so that its end contacts with the inner lower surfaces of the gripping elements 19 and separates them sufficiently 110 to allow the butt end of the whip handle to

rest upon the link 21. Now, as the whip is forced downward, it forces the pivots 11 laterally through the slots 10, against the action of the springs 28, and at the same time, the arms 18 are swung downwardly and inward, so that the clamping members 13 are brought into contact with the opposite sides of the whip handle, as illustrated in Fig. 1. It will also be seen that because of the pressure of the springs 28, the flanges 20 are caused to tightly grip the whip above the enlarged portion 29. The spring 28 is preferably formed of one strip of steel, the lower horizontal portion 30 of which lies flat upon the bottom flanges 6, so as to coact with the rivets or screws 31, which extend entirely through both sections of the casing, for holding said bottom flanges in the same plane, and as the ends 20 of this horizontal portion 30 are fitted snugly against the flanges 7, the latter are also held in a common plane by the co-operation of said elements 30 and 31.

One of the casing sections 9 has apertured strips 33 secured thereto by means of rivets 34, while the apertures 35 are adapted to receive screws or bolts for securing the whip holder to the dash-board of the vehicle. These strips 33 are preferably formed of soft steel, while the other elements may also be formed of steel, with the exception of the elements 9, the spring elements 28 and 30 being of tempered steel. The rivets or screws 36 extend through both of the opposite casing sections and hold them together.

From the foregoing, it will be seen that I have provided a whip holder of this character, which is fully capable of attaining the foregoing objects, in a thoroughly practical and efficient manner.

I do not limit my invention to the exact details of construction, combination and arrangement of parts, as herewith illustrated and described, but my invention may only 45 be limited by a reasonable interpretation of the claims.

I claim:

1. A whip holder consisting of a casing formed of two similar plates each having a 50 horizontal bottom flange and upwardly ex-

tending flanges at each of its lateral edges, each plate having two horizontally disposed recesses adjacent to its lateral edges, a pair of bell cranks each having a clamping jaw on each of its arms and being pivotally mounted in two of the opposite recesses and adapted for lateral movement therein, a strip of springy material seated upon the horizontal flanges of the casing, and fastening means extending through the opposite sections of the casing and coacting with said strip for holding its bottom flanges together in the same plane, said strip having upward extensions comprising springs which engage the bell cranks for pressing them toward each other.

2. A whip holder consisting of a pair of bell cranks each carrying a clamping jaw at the free end of each of its arms and having a pivot element rigidly secured at the junction of the arms, a casing having substantially horizontal and oppositely disposed recesses in which the pivots are slidably seated, and means for pressing the bell cranks toward each other.

3. A whip holder consisting of a pair of pivotally mounted and horizontally movable members, each having an upper clamping jaw and a lower clamping jaw, said lower clamping jaws being pivotally mounted and having their lower ends connected by a link, a spring contacting with each said member, said springs being adapted to force the members toward each other so that when a whip handle is inserted between the jaws 85 and pressed downward, the action of the springs coacts with the weight of the whip for clamping the jaws against said whip, and so that when the whip is drawn upward, the clamping jaws are drawn upward 90 therewith until their pivotal connections arrive at a plane above the pivots of said members and the action of the springs holds the jaws open.

In testimony whereof, I affix my signature, in the presence of two witnesses.

NORMAN H. COLEMAN.
